UNITED STATES PATENT OFFICE.

LESTER W. MENDELL, OF BROOKLYN, NEW YORK, ASSIGNOR TO LAWRENCE BARNUM AND JAMES J. MILDON, BOTH OF NEW YORK, N. Y.

* BOILER PLANT.

1,334,548.

Specification of Letters Patent. Patented Mar. 23, 1920.

Application filed October 3, 1916. Serial No. 123,485.

To all whom it may concern:

Be it known that I, LESTER W. MENDELL, a citizen of the United States, residing at Brooklyn, in the county of Kings, State of 5 New York, have invented certain new and useful Improvements in Boiler Plants, of which the following is a full, clear, and exact description.

My invention relates to boiler plants and 10 has for its object to produce a boiler plant provided with means for substantially preventing the formation and discharge of black smoke during the coaling period when soft coal or any fuel is used. It further 15 has for its object to provide such a plant with means for producing within the furnace substantially complete combustion for the products discharged from the stack. It further has for its object to provide means 20 for securing the above results in water tube boiler plants and increasing their efficiency.

The following is a description of an embodiment of my invention, reference being had to the accompanying drawings, in 25 which—

Figure 1 shows a transverse section of the plant on the line 1—1 Fig. 2, looking toward the front.

Fig. 2 is a longitudinal section on the line 30 2—2 Fig. 1.

Referring more particularly to the drawings, 1 is the ordinary brickwork support of the boiler having the coaling doors 2—2 and the ash doors 3—3 and the grate 4 in the 35 fire-box. 5 are the tubes of an ordinary water tube boiler, there being the ordinary upwardly extending wall 6 and baffle 7, the downwardly extending baffle 8, the headers 9 and 10 and the drum 11 connected at points 40 12 and 13 to the respective headers. 14 is the stack for discharging the products of combustion. These features are those in common use in water tube boiler plants.

In order to embody my invention in its 45 preferred form, I provide a coking arch 15 located below the forward elevated end of the water tubes 5, said arch constituting an upper wall for the fire-box, and leaving a space in front of the rear wall 6 for the passage 50 of the products of combustion among the boiler tubes and around the baffles 7 and 8 to the stack 14 and at the rear of said arch provide two steam discharge openings 16—16, to which lead pipes 17—17 which are 55 connected through valves 18—18 with the

larger pipes 19—19 which are connected to the main steam pipe 20 preferably through a valve 21. I also introduce localized abutments 22 one on each side of the drum 11 above the baffle 7 so as to slightly throttle 60 the passage for the products of combustion and retard their progress to the stack. I have found that the discharge mouths of the openings 16—16 are preferably flattened so as to be about an inch in width and one 65 quarter of an inch in height so as to spread the steam passing therethrough. I have also found that the pipes 17—17 may be made with a diameter of about one half inch, while if the pipes 19—19 are made of a diameter of one inch, satisfactory results will be produced. By making the pipes 19 and 19 70 relatively large, there is no substantial reduction in the pressure between the main pipe 20 and the pipes 17 and 17 when steam 75 is being discharged. The pipes 17 and 17 preferably discharge in a slightly downward direction, as shown in Fig. 1, so that the extended axes of said nozzles 16—16 and the streams of steam discharged therefrom are 80 along lines removed from the lower surface of the central top portion of the arch, so as not to interfere with the passage of gases from along such surface to the stack. The coking arch 15 also is preferably provided 85 with a space 23 at its front end, which permits the gases of a "flare back" to be drawn up more or less at that point and pass to the stack, eliminating the danger of having a flare back come through the charging doors 90 2—2 when open.

The axes of applicant's nozzles lie substantially in a transverse vertical plane located at the rear of the fire-box and also lie in longitudinally extending planes which 95 form an angle well below the under surface of coking arch so that steam issuing from the nozzles does not block the passage of the gases from the central portion of such under surface. The nozzles extend through 100 the side walls at points adjacent to the horizontal plane passing through the uppermost rear portion of the under surface of said coking arch. As shown, the nozzles do not extend into the fire-box any considerable 105 distance and are therefore protected by the side walls against the heat within the fire-box.

In the operation of this plant, the fire is started in the ordinary manner and when 110

once started the coking arch 15 becomes highly heated so as to tend to produce complete combustion of the gases produced within the furnace under normal working 5 conditions. When it is desired to coal, the valves 18—18 being open, so as to permit the free passage of the desired amount of steam, the valve 21 is opened, whereupon steam rushes down through the pipes 17 and 17 10 into the fire-box over the rear portion of the grate, filling this portion of the box with steam without materially interfering with the passage of the gases from the upper portion of the fire-box to the stack. The steam 15 as it passes through the hot walls is somewhat superheated before it is discharged from the nozzles. The soft coal is then introduced in the ordinary manner, and the highly heated gases coming from beneath 20 the coking arch into contact with the volatilized or partially volatilized portions of the fresh coal and mingling therewith in the presence of the injected steam, such portions are so completely consumed that as they 25 pass to the stack and are discharged therefrom, substantially no black smoke is visible. The carbon, which in the ordinary water tube boiler plant would be discharged in the form of smoke, is so consumed as to produce 30 substantially invisible products of combustion and affords heat units which are utilized in heating the boiler. After the coaling has been completed and the freshly introduced coal has been ignited to such a degree 35 that it would not give off smoke under ordinary conditions, the valve 21 is closed and permitted to remain closed until it is time to begin the next coaling operation, whereupon the steps above referred to are 40 again repeated.

As will be evident to those skilled in the art, my invention permits of various modifications without departing from the spirit thereof or the scope of the appended claims.

45 What I claim is:

1. In a boiler plant, the combination of a boiler, a setting for the same provided with a fire-box, a stack, a coking arch located below the forward portion of said boiler and leaving at the rear of said fire-box an upwardly extending passage between said coking arch and the rear wall of said fire-box for the discharge of the products of combustion, with a nozzle located in a substantially transverse vertical plane at the rear of said fire-box and pointing in a downwardly inclined direction toward the rear portion of said fire-box from one side of said fire-box, the axis of said nozzle passing below the level of the central portion of the lower surface of said arch so that the stream of discharged steam does not interfere with the free passage of gases from the lower surface of the central portion of said arch to said stack.

2. In a boiler plant, the combination of a boiler, a setting for the same provided with a fire-box, a stack, a coking arch located below the forward portion of said boiler and leaving at the rear of said fire-box an upwardly extending passage between said coking arch and the rear wall of said fire-box for the discharge of the products of combustion, the opposite side walls of said setting each having a port located in a vertical plane adjacent to the rear of said fire-box, and means for discharging steam in downwardly inclined directions into the rear of said fire-box through said ports, the axes of the discharging means passing below the level of the central portion of the lower surface of said arch so that the streams of discharged steam do not interfere with a free passage of gases from the lower surface of the central portion of said arch to said stack.

3. In a boiler plant, the combination of a boiler, a setting for the same provided with a fire-box, a stack, a coking arch located below the forward portion of said boiler and leaving at the rear of said fire-box an upwardly extending passage between said coking arch and the rear wall of said fire-box for the discharge of the products of combustion, a nozzle adjacent to the rear of said fire-box and pointing inwardly toward the rear lower portion of said fire-box, the extended axis of said nozzle within said fire-box being below the level of the lower surface of the central top portion of said arch so that the stream of discharged steam does not interfere with a free passage of gases from the lower surface of the top portion of said arch to said stack, and means for supplying steam to said nozzle.

4. In a boiler plant, the combination of a boiler, a setting for the same provided with a fire-box, a stack, a coking arch located below the forward portion of said boiler and leaving at the rear of said fire-box an upwardly extending passage between said coking arch and the rear wall of said fire-box for the discharge of the products of combustion, nozzles located on opposite sides of said fire-box adjacent to the rear of said fire-box and pointing downwardly toward rear portions thereof, extended axes of said nozzles being removed from the lower surface of the central top portion of said arch so that the streams of steam discharged from said nozzles form an angle well below the level of the under surface of said arch and do not interfere with the free passage of gases from the lower surface of the top portion of said arch to said stack, and means for supplying steam to said nozzles.

5. In a boiler plant, the combination of a boiler, a setting for the same provided with a fire-box, a stack, a coking arch located below the forward portion of said boiler and
